UNITED STATES PATENT OFFICE.

ROGER W. WOODBURY, OF DENVER, COLORADO.

WATER-BAG.

SPECIFICATION forming part of Letters Patent No. 586,650, dated July 20, 1897.

Application filed January 7, 1897. Serial No. 618,364. (No model.)

To all whom it may concern:

Be it known that I, ROGER W. WOODBURY, a citizen of the United States, residing at Denver, in the county of Arapahoe and State of Colorado, have invented certain new and useful Improvements in Flexible Rubber Bags; and I do hereby declare the following to be a full, clear, and exact description of the invention, such as will enable others skilled in the art to which it appertains to make and use the same.

My invention relates to rubber bags, and its object is to provide an improved form of this device which may be readily removed from the stopper for cleansing.

My invention consists of certain novel features of construction and combination of parts illustrated in the drawings and herein-after fully described and claimed.

20 In the accompanying drawings, Figure 1 is a side elevation of my device. Fig. 2 is a detail-longitudinal section through the upper part thereof, and Fig. 3 is a top plan view showing my valve.

25 The bag 1 is provided with the reduced neck 2. The stopper 3 is provided with an annular recess therearound, said recess being slightly larger than the neck of the bottle. Within this stopper is formed a valve-seat 4, having 30 the valve 5 therein. The countersunk button or handle 6 is adapted to open or close this valve. It will be noticed from the peculiar construction that when the valve is turned one-quarter around, or at an angle of ninety 35 degrees, the valve will be changed from its position of fully opened or entirely closed to the opposite position.

In this device the rubber bag is held to the stopper by the contractile action of the neck thereof when slipped over the outside of said 40 stopper and permitted to lie within the recess extending therearound. For this purpose the back may, if desired, be provided with a thickened portion at this point, as that will of course have a greater contractile effect. 45

It will be obvious that my device may be made in a variety of patterns and forms. I do not therefore desire to confine myself to the exact form herein illustrated, as any one skilled in the art could readily make slight 50 changes therefrom; but I desire to cover entirely all forms of this device which do not materially differ from that herein shown and described.

Having thus described my invention, what 55 I claim as new, and desire to have secured by Letters Patent, is—

The combination of a water-bag having a flexible body portion and a contracted neck, both formed of an elastic material, of a stopper having an annular groove therearound held within said neck by the contraction of the elastic material, a valve-seat formed within said stopper, a valve held within said valve-seat, and a countersunk button adapted 60 to operate said valve. 65

In testimony whereof I have signed this specification in the presence of two subscribing witnesses.

ROGER W. WOODBURY.
